UNITED STATES PATENT OFFICE.

FRITZ SCHMIDLIN, OF BADEN, SWITZERLAND, ASSIGNOR TO AKTIENGESELLSCHAFT BROWN, BOVERI & CIE., OF BADEN, SWITZERLAND.

APPARATUS FOR EFFECTING A REPEATED CLOSING OF AUTOMATIC SWITCHES.

Application filed August 7, 1922, Serial No. 580,264, and in Switzerland September 10, 1921.

This invention has for its object to provide improved automatic switches for electrical plants, so designed that after they have been opened by the effect of a disturbance, they will close again in a short time, and if they do not remain closed as a consequence of the continuance of the disturbance, they will open again, and so on, until on the disturbance continuing to operate, they will finally remain open.

This cycle of operations has been performed previously by complicated switching apparatus, the complex character of some of the parts of which involves a reduction of the degree of safety in working. In the device according to the present invention the same result is obtained in an inexpensive manner by the combination of well-known simple devices.

The improved apparatus of this invention comprises as an essential feature a delayed-action relay arranged to control the automatic device for closing the switch and to prevent any further automatic closing of the switch after the latter has been closed again *n*-times without result.

This is effected according to this invention by setting the time-mechanism of this delayed-action relay for a period comprised between an amount equal to *n*-times and (*n*±1)-times the period required for each automatic closure of the switch.

The manner of operation of the improved apparatus will now be more fully described with reference to the accompanying drawing which illustrates diagrammatically by way of example a simple embodiment of this invention.

In the improved apparatus according to this invention it is arranged that the switch shall not close again after it has been closed automatically three times in immediate succession and it has immediately opened again.

When the supply of circuit *a* which feeds the main switch *b* of the consuming network *c* is under voltage, the contact relay *d* is closed, and thereby the connecting leads for the two delayed action relays *f* and *g* (of which *f* may for example be set for ten seconds, and *g* for thirty-five seconds) are connected to the voltage of an auxiliary source of current *h*.

If the switch *b* is open, the auxiliary contacts *i* and *k* are closed. Since the relay *d* is closed, the delayed action relays are ener-

gized. The relay *f* then closes its contact after ten seconds, whereby the switching-in magnet *m* is caused to close the switch *b*, whereas the relay *g* has not yet run down. The two delayed-action relays are rendered currentless by the opening of the contacts *i* and *k* whereupon the relay *f* returns instantaneously into its zero position, whereas the relay *g* returns only gradually into its zero position.

When however, a disturbance such as an overload or a short circuit occurs in the network *c*, the switch *b* which is provided with a maximum-opening device, opens again immediately after the closing and thus closes the contacts *i* and *k*, whereby the relays *f* and *g* are caused to begin to operate again. Now the relay *f* must recommence its course from the very beginning, because it has returned into its zero position, whereas the relay *g* which has only moved back a very small extent, has on the contrary, merely to finish the uncompleted remainder of its course. After the expiration of ten seconds the relay *f* closes again the switching-in circuit of the switch *b*. If the disturbance has not yet been removed, then the switch *b* will open again, and the operation of the delayed action relay *f*, which has moved back meanwhile begins for the third time, whereas the delayed action relay *g* continues its course.

After a total period of somewhat longer than thirty seconds, the switch *b* will be closed for the third time in consequence of the relay *f* closing its contacts. If now the switch is opened again after the third closing, at this moment, that is to say, after thirty-five seconds, the delayed-action relay *g* has completed its course; it opens the contact *n* which interrupts the circuit of the auxiliary current supply *h* and renders all the relays *d*, *f*, *g*, as well as the switching-in magnet *m*, currentless. The switch *b* now remains definitely open so long as the contact *n* is held open by means of the device *o*. The contact *n* may be closed by operating the catch of the device *o*.

If the switch *b* does not open immediately after each closing, but remains closed for a certain period, the delayed-action relay *g* will in the meantime return into its zero position so that generally a definite switching off will take place solely in the case of a permanent overload or permanent short-circuit.

In practice, the opening of the auxiliary circuit, after the completion of the course of the delayed action relay g , is effected by a special relay which is caused to receive current from the contact of the relay g . The contact of this special relay can be closed again only by hand; in this case the holding-up device o is dispensed with.

The construction of the delayed-action relays is immaterial as regards the invention, but they must have the properties mentioned in the beginning hereof. They may be combined in one apparatus.

What I claim is:—

1. In a reclosing circuit breaker system, a circuit breaker having a tripping device opening said circuit breaker in response to predetermined line conditions, and automatic reclosing means comprising a reclosing coil for said circuit breaker, a first relay device actuated by the opening of the circuit breaker to energize said reclosing coil for reclosing the circuit breaker, and a second relay device having a member actuated by the opening of said circuit breaker to move from an initial position to an end position where it de-energizes itself and the circuit of said reclosing coil, the movement of said member being substantially continuous and the time required for bringing said member from its initial position to its end position being n times the period necessary for a single reclosure of the

circuit breaker, and means urging said member to return from the intermediate positions thereof to its initial position at a speed that is slow compared to its movement toward the end position. 35

2. In a reclosing circuit breaker system, a circuit breaker having a tripping device opening said circuit breaker in response to predetermined line conditions, and automatic reclosing means comprising a reclosing coil for said circuit breaker, a first relay device actuated by the opening of the circuit breaker to energize said reclosing coil for reclosing the circuit breaker, and a second relay device having a member actuated by the opening of said circuit breaker to move from an initial position to an end position where it de-energizes the circuit of said reclosing coil, the movement of said member being substantially continuous and the time required for bringing said member from its initial position to its end position being n times the period necessary for a single reclosure of the circuit breaker, and means urging said member to return from the intermediate positions thereof to its initial position at a speed that is slow compared to its movement toward the end position. 45 50

In testimony whereof I have signed my name to this specification. 55 60

FRITZ SCHMIDLIN.
